HANDBAG

Mamie E. Rohr, Lynchburg, Va.

Application February 27, 1935, Serial No. 8,562

2 Claims. (Cl. 150—29)

The present invention relates to a handbag and has for an object the provision of means in order to removably attach the frame of a handbag to the pocket or the main portion thereof. A further object of the invention is to provide a handbag in which the main or bag portion of the handbag may be interchanged for one which has been cleaned or laundered or which is of a different color.

10 Further objects will be apparent from the following description taken in connection with the accompanying drawings, in which:

Figure 1 is a side view of the complete handbag in a closed position.

15 Fig. 2 is a side view showing the frame of the bag pushed back and one side of the pocket portion removed from the frame.

Fig. 3 is a perspective view showing the frame of the bag together with the retaining members.

20 Fig. 4 is a cross-section of the frame taken on line 4—4 of Fig. 3.

Fig. 5 is a perspective view of the frame showing a modified holding means for the retaining members, and

25 Fig. 6 is a sectional view of a detail of the frame of Fig. 5.

The frame 1 of the handbag 2 is composed of two hinged members 3 which are made of any material, such as metal, celluloid, bakelite, 30 ivory, and any other suitable material. These members 3 are hinged together at 4 and each is provided with a groove 5 extending along the entire underside of each member. The pocket or main portion of the bag 6 may be made of leather or any fabric such as linen, and is preferably Shirred on the top edge 7 so as to provide a passage through which the stiff wire spring or retaining member 8 is adapted to be passed. This spring member has a bent end 9 on each end thereof and a small straight section 10. This straight section is adapted to fit into a suitable perforation 11, which is provided in each end of the grooves 5. Preferably a suitable eye member 12 surrounds each perforation 11, and, as clearly seen in Fig. 3, the straight sections 10 are adapted to enter into the perforations 11 when inserting the pocket or main portion of the handbag on to the frame. The spring wire 8, which is in the Shirred top edge 7, will force this top edge snugly into the groove 5 so that the handbag, as seen in Fig. 1, will have the appearance of having the frame portion securely and permanently attached to the bag portion in accordance with the usual constructions. The appearance of the bag, therefore, is such that it cannot

be suspected that the bag portion is removable and interchangeable from the frame members.

It is not essential that the material of the bag be Shirred on the rod or wire 8, but a casing may be formed of the same material or additional material, which may be exactly the same size as the rod.

Any suitable locking or closing device can be applied on the frame, and in the form of the invention illustrated on the drawings a closing 10 clip 13 is shown having one side thereof pivoted at 14 to one of the frame members 3. Also, any suitable handle or carrying means can be provided, for instance, a ring 15, which is attached in any suitable manner to the frame member. 15

Figs. 5 and 6 illustrate a modified construction wherein one end of the retaining members or wires 8 is each permanently secured in the members 3. The other ends of the wires are provided with a bent end 9 and a straight section 10. 20 The sections 10 fit into suitable perforations 11 in the grooves 5 similar to the construction shown in Figs. 3 and 4. The fixed ends of the wires are each provided with a bent end 9 and a ball 16 at the extreme end. This ball 16 fits permanently in a socket 17 secured in the frame member 3, and as will be seen in Fig. 6 the ball 16 may have some play in the socket so that the wire can be moved out of its groove 5 when removing or replacing the bag portion. 30

When the bag is completely assembled, as shown in Fig. 1, the wires 8 will fit snugly in the grooves 5, as illustrated in Figs. 4 and 6, except for a slight space between the wires and grooves to accommodate the material of the bag 35 portion. Also the ends 10 of the wires will penetrate almost entirely into their perforations 11. Due to spring action in the wires 8 the bag portion will be securely and attractively held in place. 40

It is, of course, obvious that if desired the frame may be interchanged for another frame having a different color or different configuration, and in this way the same bag portion is utilized. 45

I claim as my invention:—

1. A handbag comprising a frame consisting of two hinged members and each provided with a groove on the underside of the member and a socket at one end of each groove, a removable bag portion for the frame, and a spring wire for each groove to securely hold and tension the bag portion suspended from the grooves of the frame, each spring wire having a ball at one 50 55

end thereof fitting in the socket to form a permanent swivel joint for each wire on its respective member.

2. A handbag according to claim 1, in which each end of each spring wire has a bent portion and a straight section and the straight section

of one end of the wire removably fitting into a perforation in the groove and the straight section of the other end has the ball mounted thereon.

MAMIE E. ROHR. 5
